United States Patent Office

Des. 205,732
Patented Sept. 13, 1966

205,732

DISPENSING BOTTLE

Jerome Gould, Encino, Calif., assignor to Abbott Laboratories, North Chicago, Ill., a corporation of Illinois

Filed July 2, 1964, Ser. No. 80,671

Term of patent 14 years

(Cl. D58—8)

I claim:

The ornamental design for a dispensing bottle, substantially as shown.
